UNITED STATES PATENT OFFICE.

BERT KENNEDY, OF GLOVERSVILLE, NEW YORK, ASSIGNOR TO KEN-WEL SPORTING GOODS CO., OF GLOVERSVILLE, NEW YORK, A FIRM.

BASEBALL GLOVE.

Application filed September 22, 1921. Serial No. 502,360.

To all whom it may concern:

Be it known that I, BERT KENNEDY, a citizen of the United States, and a resident of Gloversville, in the county of Fulton and 5 State of New York, have invented certain new and useful Improvements in Baseball Gloves, of which the following is a specification.

This invention relates to improvements in 10 gloves and has reference more particularly to gloves used in playing the game of baseball and commonly known as fielders' gloves, and an object thereof is to produce an article of said class in which the tendency to 15 rip or tear between the fingers at their juncture with the body portion of the glove, when subjected to the strain of use, is obviated.

Another object is to produce a glove in 20 which added strength is given at the point of the base of the fingers, and withdrawing the strain at that place.

A still further object is to produce a glove in 25 which the fourchettes are welted together at the back and attached to the palm of the glove.

Another object is to produce a glove of 30 said class which will give better wear when the player brings the back of hand in contact with the dirt.

As baseball gloves of this class have heretofore been made, the palm or front portion and the front of the finger portions comprised an integral piece of material, preferably of flexible leather.

Upon this portion the fingers were built of separate pieces comprising the back and adjacent sides of the fingers, and being united to the front portion by longitudinal seams 40 and the backs of the finger portions were united to each other by transverse seams in the crotch between each of the fingers. Such construction produced the weakest portion of the glove at the point where the greatest 45 strain occurs in use, to wit: in the crotch between the fingers at the juncture of the two seams of stitching which united the front and back portions of the fingers and the back portions of the fingers with each 50 other.

In my invention the backs of the fingers are formed by three fourchettes, each fourchette constituting a half finger back, the fourchettes being welted together and

attached by welting to the palm of the glove, 55 the welts being placed at the back and joining at the tip of the fingers.

To these ends the invention includes the particular construction, combinations and arrangements of parts to be hereinafter described and particularly pointed out in the claims, reference being had to the accompanying drawings in which:

Figure 1 is a plan view of the back of a 65 fielder's glove embodying the invention.

Figure 2 is a plan view of a blank constituting one of the fourchettes, and

Fig. 3 is a transverse section through the middle fingers as taken on broken line 3—3 of Figure 1. 70

Referring now more specifically to the drawings, 5 indicates a baseball glove as a whole, the palm and front fingers being as usual integral.

The back of the glove is made up of three 75 fourchettes 6, the thumb back 7, the outer section 8 of the little finger and the wrist securing strap 9, the glove having the usual padding 10 and the linings 11. The glove is also provided with an index finger piece 76. 80

Each fourchette consists of an inner portion 6^a and the bifurcations 6^b, the whole being cut from a pattern which will give the bifurcations rounding ends and a substantially V-notch, and a squared off inner 85 end as at 6^c. These inner ends of the fourchettes are stitched to the piping 12 which surrounds the opening 13 in the back of the glove.

The edges defining the V-notch are welted 90 to the side edges of the fronts 14 of the fingers, the welts being indicated by the reference character 16, the apex of the notch being at the crotch between the fingers; the tips 15 of the fronts of the fingers are turned 95 rearwardly slightly and the edges welted to the outer ends of the adjoining fourchette sections as plainly shown in Figure 1.

The side edges of the fourchettes are welted 100 to each other along the center line of each finger at the back thereof, the welts 16 projecting beyond the outer surface and adding greater strength and wearing qualities at this particular location.

It will thus be apparent that the crotch 105 between each finger is formed of an integral portion of the back of the fingers which are the finger fourchettes and that the welts at

these crotches and at the finger tips and along the middle line of the finger backs add greater strength to the places where the strains are greatest.

5 It will also be apparent that the method of welting the fourchettes together and attaching to the palm of the gloves will tend to withdraw the strain, which usually results in early ripping of the glove at the 10 point of the base of the finger.

Furthermore, by placing the welt at the back and joining at the tip of the fingers, tendency is given to better wear when the player brings the back of the hand in contact with the dirt.

15 Having thus described my invention, what I claim as new and desire to be secured by Letters Patent, is:—

1. In a baseball glove, the combination 20 with a front member comprising a palm portion and front finger portions, of a sectional back member consisting of bifurcated fourchettes, welted together at the middle line of the finger backs and constituting the 25 finger backs, said fourchettes welted to the

front finger portions at their sides, crotch and tips.

2. A baseball glove comprising a palm portion having finger pieces, and fourchettes joined at their forward ends and along their inner edges to the finger pieces, the other edges of the fourchettes being joined directly to one another at the backs of the fingers and between the sides of the same.

3. In a baseball glove, the combination 35 with a front member comprising a palm portion and front finger portions, of a back comprising bifurcated fourchettes, each fourchette including one half of the back of each of two adjacent finger members.

4. A baseball glove comprising a front member having a palm portion and front finger portions, and a sectional back member, the sections welted to the sides and tips of the front finger portions and to each other, the welts at the back of the glove extending along the longitudinal median line of each finger and connected to the welt at the tips thereof.

BERT KENNEDY.
